UNITED STATES PATENT OFFICE.

ROY J. COOK, OF CHICAGO, ILLINOIS.

FRICITION DRAFT GEAR.

Application filed February 10, 1922. Serial No. 535,488.

To all whom it may concern:

Be it known that I, Roy J. Cook, a citizen of the United States, residing at Chicago, in the county of Cook and State of Illinois, have invented certain new and useful Improvements in Friction Draft Gears, of which the following is a specification.

This invention relates to draft gear for railway cars and its purpose is to provide an improved form of friction draft gear having an improved construction and arrangement of the parts which have a sliding frictional engagement with each other.

The principal object of the invention is to provide a draft gear comprising a pair of casings adapted to be received within the yoke and provided with friction surfaces adapted to coact with an improved arrangement of friction blocks. A further object is to provide an improved arrangement of the friction surfaces and an increased number of friction blocks whereby frictional resistance is provided in an improved and more efficient manner as compared with friction draft gears heretofore known. Other objects relate to various features of construction and arrangement which will appear more fully herein.

The nature of the invention will be understood from the following specification taken with the accompanying drawings, in which two embodiments are illustrated. In the drawings—

Figure 1 shows a horizontal sectional view through the longitudinal center line of a friction draft gear comprising one form of the present invention with a part of the structure shown in plan, the relative positions of the parts corresponding to the extended position of the draft gear.

Fig. 2 shows a longitudinal vertical section through the draft gear illustrated in Fig. 1, the section being taken on the line 2—2 of Fig. 1.

Fig. 3 is a perspective view of one of the central friction blocks embodied in the construction illustrated in Figs. 1 and 2.

Fig. 4 is a perspective view of one of the intermediate friction blocks which coact with the central friction blocks in the form illustrated in Fig. 1.

Fig. 5 is a perspective view of one of the outer friction blocks which are located outwardly of and in contact with the intermediate friction blocks in the form of construction illustrated in Fig. 1.

Fig. 6 is a perspective view of one of the spring followers.

Fig. 7 shows a transverse vertical section on the line 7—7 of Fig. 1.

Fig. 8 shows a longitudinal sectional view similar to Fig. 1 through one end of the friction draft gear, showing the relative positions of the parts when the draft gear is compressed or closed.

Fig. 9 shows a perspective view of one of the side or connecting friction wedges or blocks; and

Fig. 10 shows a longitudinal vertical section through one end of a modified form of draft gear in which the intermediate wedge blocks and outer wedge blocks are combined as integral members.

The invention is illustrated in the drawings in connection with a railway car comprising longitudinal center sills 10, having draft lugs 11 secured thereto by means of rivets 12. A yoke 13 having upper and lower arms 13^a and 13^b, respectively and a rear wall 13^c, is mounted between the sills 10 and the forward ends of these arms are provided with inturned shoulders 14 adapted to coact with the upper and lower shoulders of the coupler butt 15, which is formed integrally with the usual coupler shank 15^a. The coupler butt is secured to the arms of the yoke by means of vertical rivets 16. The yoke is supported in position between the sills 10 by means of transverse strips 17, which are secured to the lower flanges of the center sills by means of rivets or bolts 18, as shown in Fig. 7.

The improved friction draft gear comprises a pair of casings 20, which are box-like structures open at one end, these casings comprising upper walls 20^a, lower walls 20^b, rear walls 20^c and side walls 20^d. The casings are mounted in the yoke 13, with their open ends facing each other, and with their lower walls 20^b resting on the lower arm 13^b of the yoke. The end wall 20^c of one casing coacts with the vertical face of the coupler butt 15 and the end wall 20^c of the other casing coacts with the vertical rear wall 13^c of the yoke. The casings project laterally beyond the yoke and the end walls 20^c are adapted to be engaged by the draft lugs 11, carried by the center sills. The opposite side walls 20^d of each casing 20 are provided with inclined friction surfaces 22 which lie in vertical planes and converge away from the center of the draft gear.

These connecting wedges or side friction blocks have the form illustrated particularly in Fig. 9 and are adapted to extend between the casings 20 and form a connection 5 between the frictional surfaces thereon, the casings being spaced apart as shown in Fig. 1 to permit relative movement thereof when the draft gear is compressed. The friction surfaces 23 are formed on the outer sides of 10 the end portions of the connecting friction blocks or wedges 24, and the enlarged extremities on which these surfaces are formed are connected by a longitudinal web 24^a reinforced by longitudinal ribs 24^b. The 15 inner sides of the enlarged extremities of the friction blocks 24 are provided with other friction surfaces 25 which are inclined inwardly toward the center of the draft gear from the surfaces 22. The surfaces 25 are adapted to coact with inclined friction surfaces 26^a formed on the outer wedge blocks 26, having the form illustrated particularly in Fig. 5. Each wedge block 26 also has a transverse vertical surface 26^b 20 which is adapted to coact with the inner surface 20^c of the end wall 20^c of the casing 20. The blocks 26 are further provided with longitudinally extending surfaces 26^c which lie in vertical planes and are adapted to 25 coact with similarly located surfaces 27^a formed on the intermediate wedge blocks 27. The intermediate wedge blocks 27, two of which are located in each casing 20, are provided with other inclined surfaces 27^b 30 which are adapted to coact with surfaces 28^a, formed on the central wedge blocks 28. The blocks 28 are provided with end surfaces 28^b which coact with the surfaces 20^c of the casings 20 and the two surfaces 28^a 35 of each block converge inwardly toward the center of the draft gear to engage the similarly converging surfaces 27^b which are formed on the intermediate wedge blocks. 40 A spring follower 30 seats upon the end surface 27^c of the intermediate wedge blocks 27 in each casing and these followers are provided with studs 30^a adapted to engage the ends of coiled springs 31, 32 and 33 which extend between the followers in the 45 oppositely disposed casings 20 and serve as the compressible elements of the draft gear. Each spring follower is provided with laterally extending projections 30^b which are adapted to extend into notches 26^a in the blocks 26 and engage shoulders 34 which are formed on the side friction blocks 24 at the inner extremities of the friction surfaces 25. Side walls 20^d and the upper and lower walls 20^e and 20^f, respectively, are provided 50 with inturned ribs 35, which strengthen the casings and enable them better to withstand the buffing stresses. The friction surfaces on the side walls, which coact with the friction wedges 24 preferably terminate short 55 of the ends of the casings so that recesses

36 are formed between the ends of the friction surfaces and the ribs 35.

The parts of the friction draft gear illustrated in Figs. 1 to 9 inclusive, normally occupy the positions illustrated in Figs. 1 and 2. When the draw bar or coupler is moved rearwardly, the forward casing 20 is moved rearwardly by the engagement therewith of the coupler butt 15 while the other casing 20 is held in stationary position by the rear draft lugs 11 so that the two casings are thus caused to approach each other, as the rear wall 13 of the yoke moves away from the end wall 20^c of the rear casing. In a similar manner, the forward movement of the draw bar or coupler causes the rear casing 20 to be carried in a forward direction by the engagement therewith of the rear wall 13^c of the yoke, while the forward casing 20 is held in a stationary position by the forward draft lugs 11 as the coupler butt 15 moves away from the end wall of the forward casing. This movement of the two casings 20 toward each other by either a forward or rearward movement of the draw bar or coupler is adapted to effect a compression of the draft gear by causing the compression of the springs and a sliding movement of the friction surfaces on each other. When this compression takes place 95 the outer friction surfaces 23 of the side friction blocks slide toward the ends of the casings on the surfaces 22 and at the same time the ends of the side friction blocks 24 are moved inwardly due to the inclination 100 of the surfaces 22. As the endwise movement of the surfaces 23 takes place, the surfaces 25 coacting with the surfaces 26^a cause the blocks 26 to move inwardly toward the longitudinal center line of the draft gear 105 and the pressure on the blocks 27 caused by the inward movement of the blocks 26 effects a movement of the blocks 27 longitudinally of the draft gear with the surfaces 27^a sliding on the surfaces 26^c, with the surfaces 110 27^b sliding on the surfaces 28^a of the central friction blocks and with the blocks 27 also sliding on the spring followers 30. As the blocks 27 are moved longitudinally of the draft gear, they move the spring followers 115 30 in the opposite casings toward each other, thus compressing the springs 31, 32 and 33. The parts are thus caused to assume the relative positions illustrated in Fig. 8. In this way the compression of the draft gear is 120 resisted not only by the springs but also by the contacting frictional surfaces which are arranged in order to effect the maximum opposition to the compressing movement, while at the same time permitting a ready release 125 of the gear and the return of its parts to their normal positions when the strain on the draw bar or coupler is removed.

A modified form of construction is illustrated in Fig. 10 where the casing 40 is 130

provided with inclined surfaces 41, adapted to coact with the surfaces 42 formed on the outer sides of the side friction blocks 43. The inner sides of the blocks 43 are provided with inclined surfaces 44 similar to those previously described and adapted to coact with the inclined surfaces 45^a formed on the intermediate friction blocks 45. These blocks are provided with end surfaces 45^b adapted to rest on the surfaces 40^a formed on the end walls of the casings, when the gear is expanded, and the blocks 45 are further provided with inclined surfaces 45^c which coact directly with the inclined surfaces 46^a of the central friction blocks 46. These central friction blocks are similar to those previously described and coact with the surfaces 40^a of the end walls of the casing but have no movement thereon. The intermediate friction blocks 45 are further provided with transverse vertical surfaces 45^d which engage the spring followers 47. These spring followers are provided with lateral projection 47^a adapted to engage the shoulders on the side friction blocks 43 and they are also provided with central lugs 47^b which engage the ends of the coil springs 48, 49 and 50. This form of construction differs from that previously described merely in the combination of the outer friction blocks and intermediate friction blocks in the integral members 45.

Although certain forms of the invention have been shown and described for the purpose of illustration, it will be understood that it may be constructed in various other embodiments without departing from the scope of the attendant claims.

What I claim is:

1. A draft gear comprising a pair of box-like casings having their open ends facing each other, said casings having side walls provided with inclined surfaces, side friction blocks extending between opposite casings and having outer inclined surfaces coacting with the inclined surfaces of said side walls, said side friction blocks having inner inclined surfaces, intermediate friction blocks actuatable by said side friction blocks, central friction blocks coacting with said intermediate friction blocks, spring followers engaging said intermediate friction blocks, and springs extending between opposite casings and engaging said spring followers.

2. A draft gear comprising a pair of casings, each of said casings comprising a pair of side walls and an end wall, said side walls being provided with inclined friction surfaces, side friction blocks having outer inclined surfaces to coact with the inclined surfaces on said side walls, said side friction blocks being provided at their ends with inner inclined surfaces, outer friction blocks coacting with said inner inclined surfaces

and with said end walls, wedging means, intermediate friction blocks coacting with said outer friction blocks and said wedging means, spring followers engaging said intermediate friction blocks, and a spring 70 extending between said spring followers.

3. A draft gear comprising a pair of casings, each of said casings comprising a pair of side walls and an end wall, said side walls being provided with inclined friction surfaces, side friction blocks having outer inclined surfaces to coact with the inclined surfaces on said side walls, said side friction blocks being provided at their ends with inner inclined surfaces, outer friction blocks 75 coacting with said inner inclined surfaces and with said end walls, intermediate friction blocks coacting with said outer friction blocks, said outer friction blocks having inner surfaces extending parallel with the longitudinal axis of the draft gear, intermediate friction blocks having outer surfaces adapted to coact with said inner surfaces of said outer friction blocks, said intermediate friction blocks being provided on their inner sides with inclined friction surfaces, and central friction blocks coacting with the inner inclined surfaces of said intermediate friction blocks and with said end walls. 80

4. A draft gear comprising a pair of casings, each of said casings comprising a pair of side walls and an end wall, said side walls being provided with inclined friction surfaces, side friction blocks having outer inclined surfaces to coact with the inclined surfaces on said side walls, said side friction blocks being provided at their ends with inner inclined surfaces, outer friction blocks 105 coacting with said inner inclined surfaces and with said end walls, intermediate friction blocks coacting with said outer friction blocks, said outer friction blocks having inner surfaces extending parallel with the longitudinal axis of the draft gear, intermediate friction blocks having outer surfaces adapted to coact with said inner surfaces of said outer friction blocks, said intermediate friction blocks being provided on their inner sides with inclined friction surfaces, central friction blocks coacting with the inner inclined surfaces of said intermediate friction blocks and with said end walls, spring followers 110 engaging said intermediate friction blocks, and a spring extending between said spring followers.

5. A draft gear comprising a pair of casings, said casings each being provided with side walls and an end wall, said side walls being provided with inner surfaces inclined to the longitudinal axis of the draft gear, said side walls being recessed at the ends of said inclined surfaces opposite said end walls, side friction blocks having enlarged 115

extremities provided with outer inclined surfaces adapted to coact with the inclined surfaces on said end walls, said enlarged extremities being provided with inner inclined surfaces, friction blocks coacting with said inner inclined surfaces, and compressible mechanism located between and actuatable by said last named friction blocks.

6. A draft gear comprising a pair of casings, said casings each being provided with side walls and an end wall, said side walls being provided with inner surfaces inclined to the longitudinal axis of the draft gear, said side walls being recessed at the ends of said inclined surfaces opposite said end

walls, side friction blocks having enlarged extremities provided with outer inclined surfaces adapted to coact with the inclined surfaces on said end walls, said enlarged extremities being provided with inner inclined surfaces, friction blocks extending between and engaging said inner inclined surfaces, spring followers coacting with said last-named friction blocks and having parts adapted to engage said shoulders, and a spring extending between said spring followers.

In testimony whereof, I have subscribed my name.

ROY J. COOK.
